ABSTRACT OF THE DISCLOSURE

A ternary comparator utilizing multi-input ternary threshold logic elements for performing ternary arithmetical operations.

This is a divisional application of the commonly assigned copending application of W. H. Hanson, Ser. No. 491,594, filed Sept. 30, 1965 and entitled "Signed Ternary Carry Generator."

Both the conventional and signed ternary number systems, along with associated arithmetical operations, are defined and discussed in Patent No. 3,210,529 issued Oct. 5, 1965 to W. H. Hanson and assigned to the assignee of the present invention.

Conventional ternary comparator networks are generally serial in nature and consist of a serial arrangement of ternary comparator stages such as those disclosed in a paper by W. H. Hanson entitled "Ternary Threshold Logic," published in IEEE Transactions on Electronic Computers, vol EC-12, pp. 191-197, June 1963. Serial networks of this type require a relatively large number of elements and logic levels to effect. Some further properties of ternary threshold logic are discussed in a note by R. Merrill entitled "Some Properties of Ternary Threshold Logic" published in IEEE Transaction on Electronic Computers, vol. EC-13, pp. 632-635, October 1964.

It has been determined that a comparison, through the jq^{th} digit-order, of two ternary words of the form $A_n \dots A_k \dots A_1$ and $B_n \dots B_k \dots B_1$ is represented by the logical function,

$$K_{jq} = 2w_q A_{qj} t^{2w_q \bar{B}_{qj} + \dots + 2w_i A_{q(i-1)} + \dots + 2w_1 A_{q(1-1)} + 2w_1 \bar{B}_{q(1-1)} + t K_{q(1-1)}}$$

It is proposed by this invention to reduce the number of elements and logic levels necessary to generate signals representative of signed ternary comparisons by utilizing these determinations and their logical equivalents.

The invention is effected by employing multi-input ternary threshold logic elements. There are a variety of circuits available, capable of performing the logical threshold function, which are well known in the art (such as described by R. Schauer et al. in "Some Applications of Magnetic Film Paramatrons As Logical Devices" IRE, Transactions on Electronic Computers, vol. EC-9, pp. 315-320, September 1960) and these circuits, of themselves, do not constitute a part of this invention.

The output, Y , of a ternary threshold logic element having n inputs $X_n \dots X_k \dots X_1$ with associated weights $w_n \dots w_k \dots w_1$, where $w_k \geq 1$, and threshold t , where

$$1 \leq t \leq \sum_{k=1}^n w_k$$

can be represented as follows:

$$Y = w_n X_n t \dots t w_k X_k t \dots t w_1 X_1$$

2

The value of the ternary threshold logic function, Y is determined as follows:

In the signed ternary number system;

$$Y = +1 \text{ if } \sum_{k=1}^n w_k X_k \geq t$$

$$Y = -1 \text{ if } \sum_{k=1}^n w_k X_k \leq -t$$

$Y = 0$ in all other cases, where $X_k = +1, 0, -1$, and in the conventional ternary number system;

$$Y = 2 \text{ if } \sum_{k=1}^n w_k (X_k - 1) \geq t$$

$$Y = 0 \text{ if } \sum_{k=1}^n w_k (X_k - 1) \leq -t$$

$Y = 1$ in all other cases, where $X_k = 2, 1, 0$.

20 It will thus be seen that by implementing the determinations set forth above with multi-input ternary threshold logic elements, a comparison of two ternary words can be realized in a relatively short period of time utilizing a relatively small number of elements. The novel features which are considered characteristics of this invention are set forth with particularity in the appended claims. The invention itself, both as to its organization and method of operation, as well as additional advantages thereof, will be best understood from the following description when read in connection with the accompanying drawings, in which:

25 The figure is a logical block diagram of a preferred embodiment of a comparator designed in accordance with this invention.

30 The drawing generally shows block diagrams of a basic comparator designed in accordance with the present invention. In the figure each of the blocks represent a multi-input ternary threshold logic element. The term appearing within each of the blocks represents the threshold of the element. The term appearing at each input to each of the elements represents the weight accorded the associated input.

35 With reference now to the figure, a logical block diagram of a comparator according to the present invention is shown. The comparator, for generating a signal, K_n , representative of a comparison of two ternary words of the form $A_n \dots A_k \dots A_1$ and $B_n \dots B_k \dots B_1$, comprises m multi-input ternary threshold logic elements arranged in m logic levels. The number of elements, m necessary to generate K_n is given by, $\langle n/q \rangle$, where:

40 $\langle n/q \rangle = n/q$, if the quotient is an integer,
 $= n/q$ rounded up to the next higher integer,
45 if the quotient is not an integer,
 $q = p-1)/2$, and p is the number of distinct input signals allowed per element.

50 Each of the elements, $j=1 \dots m-1$, receives $2q$ signal representations of digit-orders $A_{qj} \dots A_{q(j-1)+1}$ and $\bar{B}_{qj} \dots \bar{B}_{q(j-1)+1}$, of the words to be compared, A and B , and a signal representation of $K_{q(j-1)}$, the signal generated by the next lower order element. Each of these elements generates a signal K_{qj} , representative of a comparison through the qj digit order. The mth element receives $2r$ signal representations of digit-orders $A_n \dots A_{n-r+1}$ and $\bar{B}_n \dots \bar{B}_{n-r+1}$, of words to be compared, A and B , and a signal representation of K_{n-r} , the signal generated by the $(m-1)^{\text{th}}$ element, where r is the non-zero remainder of n/q . If the remainder of n/q is zero then $r=q$. The mth element generates a signal representative of K_n .

Each of the elements $j=1 \dots m-1$ has a threshold of $t(t=1 \dots)$ and is coupled so as to receive $2q+1$ input signals representative of digit-orders

$$A_{qj} \dots A_{q(j-1)+1}$$

$\bar{B}_{qj} \dots \bar{B}_{q(j-1)+1}$, and $K_{q(j-1)}$, the latter being representative of the signal generated by the next lower order element. Each of said digit-order inputs is weighted by a factor $2W_i = (2t)(3^{i-1})$ and $K_{q(j-1)}$ is weighted by a factor of w_1 . The jth element utilizes said digit-order and comparison signals to generate a signal in accordance with the logical function:

$$K_{qj} = 2w_q A_{qj} \cdot 2w_q \bar{B}_{qj} \cdot \dots \cdot 2w_i A_{q(j-1)+i} \cdot 2w_i \bar{B}_{q(j-1)+i} \cdot \dots \cdot 2w_1 A_{q(j-1)+1} \cdot 2w_1 \bar{B}_{q(j-1)+1} \cdot t K_{q(j-1)}$$

where $j=1 \dots m-1$ and for each j , $i=1 \dots q$.

The mth element has a threshold of t and is coupled so as to receive $2r+1$ input signals representative of digit-orders $A_n \dots A_{n-r+1}$, $\bar{B}_n \dots \bar{B}_{n-r+1}$, and K_{n-r} , the latter being representative of the signal generated by the $(m1)^{\text{th}}$ element. Each of said digit-order inputs is weighted by a factor $2W_i = (2t)3^{i-1}$ and K_{n-r} is weighted by a factor of w_1 . The mth element utilizes said digit-order and comparison signals to generate a signal in accordance with the logical function:

$$K_n = 2w_r A_n \cdot 2w_r \bar{B}_n \cdot \dots \cdot 2w_i A_{n-r+1+i} \cdot 2w_i \bar{B}_{n-r+1+i} \cdot \dots \cdot 2w_1 A_{n-r+1} \cdot 2w_1 \bar{B}_{n-r+1} \cdot t K_{n-r}$$

where; $i=1 \dots r$.

Control signal, K_0 , an input to the first element, determines what condition K_n will detect, in accordance with the following:

$$K_0=1$$

$$K_{n-1} \text{ implies } A \geq B$$

$$K_{n-1} = -1 \text{ implies } A < B$$

$$K_0=0$$

$$K_{n-1} \text{ implies } A > B$$

$$K_{n-1} = 0 \text{ implies } A = B$$

$$K_{n-1} = -1 \text{ implies } A < B$$

$$K_0=-1$$

$$K_{n-1} = 1 \text{ implies } A > B$$

$$K_{n-1} = -1 \text{ implies } A \geq B$$

Following are two illustrative examples of specific ternary comparators designed in accordance with this invention.

Let $p=5$, $t=1$, and $n=30$. Then $q=2$, $m=15$, $r=2$, and $2w_1=(2)(3^{1-1})$.

With these parameters given the specific comparator is defined by the following logical functions.

First Element: $K_2 = 6A_2 \cdot 6\bar{B}_2 \cdot 12A_1 \cdot 12\bar{B}_1 \cdot K_0$

Second Element: $K_4 = 6A_4 \cdot 6\bar{B}_4 \cdot 12A_3 \cdot 12\bar{B}_3 \cdot K_2$

Third Element: $K_6 = 6A_6 \cdot 6\bar{B}_6 \cdot 12A_5 \cdot 12\bar{B}_5 \cdot K_4$

Fourth Element: $K_8 = 6A_8 \cdot 6B_8 \cdot 12A_7 \cdot 12\bar{B}_7 \cdot K_6$

* * * * *

j^{th} Element: $K_{2j} = 6A_{2j} \cdot 6\bar{B}_{2j} \cdot 12A_{2j-1} \cdot 12\bar{B}_{2j-1} \cdot K_{2j-2}$

* * * * *

Fourteenth Element: $K_{28} = 6A_{28} \cdot 6\bar{B}_{28} \cdot 12A_{27} \cdot 12\bar{B}_{27} \cdot K_{26}$

Fifteenth Element: $K_{30} = 6A_{30} \cdot 6\bar{B}_{30} \cdot 12A_{29} \cdot 12\bar{B}_{29} \cdot K_{28}$

Let $p=7$, $t=1$, and $n=29$. Then $q=3$, $m=10$, $r=2$, and $2w_1=(2)(3^{1-1})$. With these parameters given the specific comparator is defined by the following logical functions.

First Element: $K_3 = 18A_3 \cdot 18\bar{B}_3 \cdot 16A_2 \cdot 16\bar{B}_2 \cdot 12A_1 \cdot 12\bar{B}_1 \cdot K_0$

Second Element: $K_6 = 18A_6 \cdot 18\bar{B}_6 \cdot 16A_5 \cdot 16\bar{B}_5 \cdot 12A_4 \cdot 12\bar{B}_4 \cdot K_3$

* * * * *

j^{th} Element:

$K_{3j} = 18A_{3j} \cdot 18\bar{B}_{3j} \cdot 6A_{3j-1} \cdot 16\bar{B}_{3j-1} \cdot 12A_{3j-2} \cdot 12\bar{B}_{3j-2} \cdot K_{3(j-1)}$

* * * * *

Ninth Element:

$K_{27} = 18A_{27} \cdot 18\bar{B}_{27} \cdot 16A_{26} \cdot 16\bar{B}_{26} \cdot 12A_{25} \cdot 12\bar{B}_{25} \cdot K_{24}$

Tenth Element: $K_{29} = 6A_{29} \cdot 6\bar{B}_{29} \cdot 12A_{28} \cdot 12\bar{B}_{28} \cdot K_{27}$

The number of distinct input signals allowed per element, p (or the total number of input signals allowed per

element) is determined by the specific type of hardware utilized to implement the invention. The factor t , which is utilized in determining the threshold of the various elements is preferably one; however any other integral value will render the invention operative.

5 What is claimed is:

1. A ternary comparator for generating a signal K_n , representative of a comparison of two words of the form $A_n \dots A_k \dots A_1$ and $\bar{B}_n \dots \bar{B}_k \dots \bar{B}_1$, comprising:

10 m multi-input ternary threshold logic elements for generating a signal representation K_n , each of said signal generating elements $j=1 \dots M=1$, coupled to the next lower signal generating element for generating a signal representative of K_{qj} , a comparison through qj^{th} digit-order of $A_n \dots A_k \dots A_1$ and $\bar{B}_n \dots \bar{B}_k \dots \bar{B}_1$, comprising:

input means for receiving signal representations of digit orders $A_{qj} \dots A_{q(j-1)+1}$,

$$\bar{B}_{qj} \dots \bar{B}_{q(j-1)+1}$$

and
a multi-input ternary threshold logic element coupled to said input means for utilizing said digit-order and comparison signals to generate K_{qj} in accordance with the logical function,

$$K_{qj} = 2w_q A_{qj} \cdot 2w_q \bar{B}_{qj} \cdot \dots \cdot 2w_i A_{q(j-1)+i} \cdot 2w_i \bar{B}_{q(j-1)+i} \cdot t K_{q(j-1)}$$

said signal generating element, $j=m$ coupled to the next lower signal generating element for generating a signal representative of K_n , comprising:

input means for receiving signal representations of digit orders $A_n \dots A_{q(m-1)+1}$,

$$\bar{B}_n \dots \bar{B}_{q(m-1)+1}$$

and
a multi-input ternary threshold logic element coupled to said input means for utilizing said digit-order and comparison signals to generate K_n in accordance with the logical function

$$K_n = 2w_r A_n \cdot 2w_r \bar{B}_n \cdot \dots \cdot 2w_i A_{n-r+1+i} \cdot 2w_i \bar{B}_{n-r+1+i} \cdot t K_{n-r}$$

2. A comparator as defined in claim 1 in which each of said multi-input ternary threshold logic elements is a signed ternary threshold logic element, said elements being arranged such the comparison signal K_n is generated in m logic levels.

3. A comparator as defined in claim 2 in which m is defined by the function $\langle n/q \rangle$, $q=(p-1)/2$, p is the number of distinct input signals per threshold element, and r is the non-zero remainder of n/q .

4. A signal generating element for generating a signal K_{qj} , representative of a comparison through the qj^{th} digit-order of two ternary words of the form $A_n \dots A_k \dots A_1$ and $\bar{B}_n \dots \bar{B}_k \dots \bar{B}_1$, comprising:

55 input means for receiving signal representations of digit orders $A_{qj} \dots A_{q(j-1)+1}$, $\bar{B}_{qj} \dots \bar{B}_{q(j-1)+1}$ and comparison signal $K_{q(j-1)}$, the latter being representative of the comparison signal generated by a next lower element, and

a multi-input ternary threshold logic element coupled to said input means for utilizing said digit-order and comparison signals to generate a signal representative of K_{qj} in accordance with the logical function,

$$K_{qj} = 2w_q A_{qj} \cdot 2w_q \bar{B}_{qj} \cdot \dots \cdot 2w_i A_{q(j-1)+i} \cdot 2w_i \bar{B}_{q(j-1)+i} \cdot t K_{q(j-1)}$$
